JAR OR THE LIKE

Walter J. Landor, San Francisco, Calif., assignor to Hills Bros. Coffee, Inc., San Francisco, Calif.

Filed Sept. 20, 1968, Ser. No. 13,628

Term of patent 14 years

Int. Cl. D9—01

U.S. Cl. D9—150

FIG. 1

FIG. 2

FIG. 4

FIG. 3

FIG. 1 is a front elevational view of a jar or the like embodying my new design, the rear being substantially the same in appearance;

FIG. 2 is a side elevational view, the opposite side being substantially the same in appearance;

FIG. 3 is a top plan view thereof; and

FIG. 4 is a bottom plan view thereof.

I claim:

The ornamental design for a jar or the like, as shown and described.
